Primary Examiner — Susan Moon Lee(74) *Attorney, Agent, or Firm* — Michael R. Shevlin**CLAIM**

The ornamental design for a game, as shown and described.

DESCRIPTION

FIG. 1 is a perspective view of a game having a game board with detachable wings in an assembled state with four matching sets of game pieces and matching die in accordance with the design of my invention;

FIG. 2 is a top plan view of the game of FIG. 1;

FIG. 3 is a bottom plan view of the game of FIG. 1;

FIG. 4 is a front end view of the game of FIG. 1;

FIG. 5 is a rear end view of the game of FIG. 1;

FIG. 6 is a left side view of the game of FIG. 1;

FIG. 7 is a right side view of the game of FIG. 1;

FIG. 8 is a perspective view of the game of FIG. 1 showing the game board in an un-assembled state with the detachable wings being detached; and,

FIG. 9 is a perspective view of the game of FIG. 1, with the four matching sets of game pieces in position on the game board.
